UNITED STATES PATENT OFFICE.

NEIL SINCLAIR, OF OAKLAND, CALIFORNIA, ASSIGNOR TO RIP VAN WINKLE WALL BED COMPANY, INC., OF OAKLAND, CALIFORNIA, A CORPORATION OF CALIFORNIA.

FOLDING BED.

Application filed November 22, 1921. Serial No. 516,939.

My invention relates to improvements in folding beds and more particularly to that type of foldable bed which is attached to a vertically pivoted door so that by turning the 5 door, the bed may be positioned either in the room or in a recess opening therefrom.

It is generally desirable to attach the bed to a door of less width than the bed itself and to provide a narrow side door which will 10 allow the overhanging portion of the bed to swing into the recess. The recess is also used as a clothes closet, the narrow door giving access to the recess when the bed is in the room but due to the overhanging of the bed, 15 the door is blocked when the bed is within the closet. Thus each time it is desired to enter the closet it is necessary to swing the bed into the room.

My improved invention aims to provide 20 means for carrying a bed on the pivotally mounted door so that access may be had to the closet with the bed either in the room or in the closet. With my improved invention, a vertically pivoted door, narrower than the 25 width of the bed is used, together with a narrow side door and means is provided for shifting the bed laterally as the door is reversed so that the overhang of the bed on the pivoted door or in fact the extension of the 30 bed beyond the door always comes on the side opposite the narrow entrance door.

It is one of the objects of my invention to provide a structure which will allow entrance into the closet through the narrow 35 door with the bed in either position and to avoid the objection to turning the bed into the room each time entrance to the closet is desired.

With these and other objects in view my invention consists in certain novel features of construction, combinations and arrangements of parts herein shown and described and more particularly pointed out in the appended claims.

By referring to the accompanying drawings and specifications my invention will be understood.

Figure 1 is an elevation of the bed folded or upended and positioned on the outside of 50 the closet.

Fig. 2 is a plan view of the bed and closet, and also showing in dotted outlines the position of the bed when within the closet.

Fig. 3 is an enlarged sectional view on the 55 line 3-3, Figure 2.

Fig. 4 is a view in elevation of the bottom of the door and associated mechanism.

Fig. 5 is a view in perspective of a reinforced plate used at the bottom of the door.

Fig. 6 is a view in plan of the operating 60 gears for causing lateral movement of the bed with respect to the door.

Fig. 7 is a vertical section through the pivot plate on which the door is mounted.

Fig. 8 is a view in section through the 65 lower end of the tubular bed supporting member and the operating gear attached thereto.

Throughout the figures similar numerals 70 refer to identical parts.

The numeral 1 denotes the room wall in which is formed a recess or closet 2. At one side this recess extends beyond the wall opening 3, forming a pocket 4. The wall opening is closed by a closet door 5 hinged to the casting, as shown at 6, and by a second door 7 pivotally mounted on a central vertical axis as shown at 8 and 9.

The wall bed comprises a head frame 10 from which may extend brackets 11 to which 80 the folding portion of the bed is pivotally attached as indicated at 12.

Attached to the face of the door are brackets 13 and 14 in which is pivotally mounted a tubular member 15 and rigidly attached to 85 the latter are supporting arms 16 and 17. These arms, on their outer end, are provided with pivot pins 18.

At the center of the horizontal rail of the head frame 10 is attached member 19 having 90 preferably a laterally extending arm 20 which is pivotally mounted on the pin 18 of the upper arm 16.

Extending between the lower ends of the side posts of the head frame is an angle bar 95 21 at the center of which is attached a member 22, extending rearwardly and being provided with an opening by which it is pivotally mounted on the pin 18 of arm 17.

The means by which the lower edge of the door is pivotally mounted, comprises a plate 23 which is fastened to the floor in any suitable manner, and which is provided with an upwardly extending hub 24 which serves to center a toothed gear 25. The latter may be held in non-rotatable relation with the plate by means of pins 26 that project upwardly from the latter and engage openings in the side of the gear. A pin 27 extends upwardly from the hub into a corresponding hole in the 100 105 110

bottom of the door so that the door is adapted to pivot on this pin.

To prevent the material of the door from breaking out at the point where pin 27 enters, 5 I provide the reinforcing plate 28. This plate comprises the flat portion 29 which is attached to the face of the door by means of screws passing through the holes 30. It is further held to the door by means of bolts 31 10 which pass through the elongated openings 32 and bolt the bracket 14 in position.

I cut and bend a strip 33 at right angles to the plate 29 and provide therein an opening 34 having the same diameter as the pin 15 27. This bent portion 33 is inserted in a saw slot cut in the door with the opening 34 positioned in alignment with the hole for pin 27. By this construction the strains 20 on the door which tend to tear the pin through the wood, are transmitted to the reinforcing plate and thus obviates the danger of the pin breaking through the bottom of the door.

Meshing with gear 25 is a toothed gear 25 36 which has a diameter slightly larger than gear 25 due to the fact that when the door 7 turns through 180° the supporting brackets 16 and 17 turn through a slightly smaller angle.

30 Gear 36 is attached rigidly to the lower end of the tubular member 15. The preferred means of attaching this gear 36 comprises a plug 37 held in the lower end of the member 15 by pins 38. This plug has 35 an axially extending hub 39 to which the gear 36 is keyed as shown at 40.

To prevent movement of the bed on the pivot pins 18 except when the door is moved, I provide a guide rod 41 the ends of which 40 are attached to the angle 21 and to the side post of the head frame 10. This rod engages an opening in the bracket 42 which is attached to one edge of the door, the opening being elongated in order to allow the 45 rod to assume an angular direction as the bed is moved by the supporting arms.

When the bed is in the closet as illustrated in Figure 2, the tendency for a person reaching through the opening of the narrow door 50 is to grasp the side of the bed frame 10 to move it out. But the pressure thus exerted tends to rotate the supporting arms in the opposite direction from that necessary to rotate the door and in order to prevent 55 any undue strain on the parts I provide a stop which is operative when an attempt is made to rotate the door by grasping the bed but is non-operative when the movement is made by pressure on the door. This stop 60 consists of a block 43 attached to the floor of the closet and an arm 44 attached to one side of the angle 21. By this arrangement, when the bed itself is pulled in an outward direction, movement is prevented by contact 65 between the bar and stop. But when

the door is pulled outwardly, the motion through the gears is transmitted to the supporting arms and the bed itself takes a rearwardly and sidewise movement so that the arm clears the stop.

With the bed positioned within the closet as shown in Figure 2 the operation is as follows: The narrow door 5 is opened and panel 7 swings in a clockwise direction on its pivots. This moves the gear 36 in a planetary manner around the stationary gear 25 and so causes its rotation. This movement is transmitted to the shaft 15 and thus to the arms 16 and 17. As the panel 7 turns, the bed moves out of the closet 30 through the opening of door 5, and at the same time the arms 16 and 17 shift the bed from one side of the panel to a corresponding position on the opposite side. By this method of mounting the bed on the door 35 panel, a minimum width of wall opening is required and the bed always overhangs the panel at the side opposite the entrance door, giving free access through the latter, when the bed is either closed or open and 40 when it is in the closet or the room, and leaves at all times available and accessible the closet space behind the door 5.

While I have shown automatic means for shifting the bed laterally on the door panel, 45 it will be apparent that the gears for this purpose may be omitted and the shifting produced manually. The mattress supporting frame is pivoted to swing in a vertical direction and is provided with suitable balancing devices, but as they form no part of the present invention I have not shown them in detail.

While I have shown the bed and the vertical rod 15 as mounted on a panel and the panel pivoted between the floor and ceiling it will now be clear that the supporting axis may be pivoted from movable bearings or arms which in turn are pivotally mounted between the floor and ceiling, and if desired 50 the panel may then be supported from the said axis.

Although I have shown and described my invention as employing a supplemental closet door 5 hinged to swing about the vertical edge of the opening in a conventional manner it will be seen that I may employ in place thereof a sliding door without departing from the spirit of my invention.

Although I have described the doors 7 55 and 5 as relatively wide and narrow doors I wish it understood that these are merely words of identification without intent to restrict the doors to any relative dimensions as either one may be wider than the other or they may both be the same, according to the taste and requirements of individual builders; and the relative width of closet door 5 as compared with the door on which the bed is mounted is immaterial.

I claim:

1. A bed mounted on a relatively narrower panel, said panel rotatable about a vertical axis, a hinged door adjacent the panel and adapted when opened to allow the bed to pass through the opening so formed, means supporting the bed in combination with the said panel and admitting of a lateral displacement of the bed with respect to the 10 face of the panel, and means forcing said lateral displacement as said panel is rotated whereby the bed both before and after rotation of the panel is forced to extend substantially beyond that edge of the panel then remote 15 from said door and leave unobstructed the passageway closed by said door.

2. Mechanism as set forth in claim 1 20 wherein there is a vertical shaft supported from said panel and having arms extending therefrom, and wherein said bed is pivotally mounted between the ends of said arms.

3. Mechanism as set forth in claim 1 25 wherein there is a vertical shaft supported from said panel and having arms extending therefrom, and wherein said bed is pivotally mounted between the ends of said arms, and wherein said means comprise gear mechanism adapted to rotate said shaft as said panel is rotated.

4. Mechanism as set forth in claim 1 30 wherein there is a vertical shaft supported from said panel and having arms extending therefrom, and wherein said bed is pivotally mounted between the ends of said arms, and wherein said means comprise gear mechanism adapted to rotate said shaft as said panel is rotated, and a guide rod 35 restraining the bed from rotating with respect to the panel but permitting its lateral displacement.

5. In a mounting for a disappearing bed, 40 a pair of arms carried on a vertical member and adapted to pivotally support on a first vertical axis a folding bed therebetween, said member carried in bearings, a wall panel carrying said bearings, said panel movable on a second vertical axis and connecting 45 mechanism between the member and the second axis compelling the rotation of the member about the first axis as the panel is rotated about the second axis.

6. A bed in combination with a relatively 50 narrower panel and rotatable about a vertical axis within an opening wider than said panel, a door adjacent the panel and adapted when opened to allow the bed to pass through the opening so formed and when 55 closed to effect closure of the said opening with the said panel, means supporting the bed displaced from the said axis and admitting of a lateral displacement of the bed with respect to the face of the panel, and

means forcing said lateral displacement as 60 said panel is rotated about said axis whereby the bed both before and after rotation of the panel is forced to extend substantially beyond that edge of the panel then remote 65 from said door and leave unobstructed the 70 passageway closed by said door.

7. A bed rotatably mounted in combination with a relatively narrow panel, and laterally displaceable with respect thereto, 75 said panel positioned on one side of an opening and adapted to partially close said opening, pivots on which said panel is adapted to rotate about a vertical axis, a door adjacent the panel adapted to close the remainder of the said opening and 80 adapted when open to allow the bed to pass through the opening so formed, and means forcing the lateral displacement of the bed with respect to the panel as the bed is rotated about said axis whereby the bed both 85 before and after rotation of the panel is forced to extend substantially beyond that edge of the panel then remote from said door and leave unobstructed the passage- 90 way closed by said door.

8. The combination with a revoluble door pivoted approximately midway between its sides, of a folding bed of greater width than said door mounted to revolve therewith, and means for automatically shifting said bed 95 transversely with respect to said door upon a revolving movement thereof.

9. The combination with a revoluble door, 100 of a bed of greater width than said door pivotally connected thereto, to revolve therewith, one side of said bed being normally disposed approximately flush with one side edge of the revoluble door, and means for automatically shifting said bed to dispose the opposite edge thereof approximately 105 flush with the opposite side edge of the door upon approximately a half revolution of the door.

10. The combination with a panel mounted to revolve upon an axis positioned intermediate its side edges, of a pair of horizontally disposed pivotally mounted arms, a bed frame pivotally mounted on said arms, said panel, arms and frame being mounted to turn in unison about the panel pivot, and means in connection with said panel and arms 110 to effect a swinging of the frame forward, relative to the panel, upon rotation of the panel.

11. The combination with a panel mounted to revolve upon an axis positioned intermediately its side edges, of a pair of horizontally disposed pivotally mounted arms, a bed frame pivotally mounted on said arms, said panel, arms and frame being 115 mounted to turn in unison about the panel pivot, and means including a gear mechanism, in connection with said panel, arms 120

and frame, to effect a swinging of the frame forward, relative to the panel, upon rotation of the panel.

12. The combination with a door adapted to swing about a vertical axis, of an arm mounted to swing in unison therewith, a bed frame pivotally mounted on said arm, a

fixed arcuate rack concentric with the door axis and gear means operatively connecting said arm and rack, whereby the arm is ¹⁶ swung to shift the bed frame relative to the door as the door is rotated.

NEIL SINCLAIR.
